PACK BOARD HARNESS

Norman D. Ashwood, Victoria, British Columbia, Canada

Application April 8, 1947, Serial No. 740,172

3 Claims. (Cl. 224—8)

1

This invention relates to a harness for packs. An object of the invention is the provision of a device for forming a pack in which a relatively stiff light frame has a plurality of cords or lines attached thereto with spaced rings for receiving cords into a compact mass, one of the last-mentioned cords being readily released to permit egress to the pack while the other cord or cords retaining the main body of the pack intact for retaining the articles therein in compact relation.

Another object of the invention is the provision of a device for packing articles so that the same may be readily carried by shoulder straps in a convenient manner on the body of a person, said device including a relatively stiff base upon which is mounted a piece of fabric for enclosing articles, the articles in the fabric being bound together by bracing cords attached at points on the periphery of the base and directed radially toward the top of the pack when said cords terminate in rings which receive a cord forming a draw-string and constrained to an elliptical formation over the top of the pack when drawn up tight and fastened at its ends to one of the rings, a cord forming a second draw-string received by rings intermediate the ends of the bracing cords being employed for retaining the side walls of the pack in a substantially vertical manner and the articles therein in a compact mass when the first draw-string has been loosened.

A further object of the invention is the provision of a device for packing articles in which a relatively stiff and light frame forms a base upon which is laid a piece of fabric of sufficient dimensions for completely covering articles neatly confined and stacked on said base, a harness formed of stout cords or other suitable materials having one of the ends thereof attached to the periphery of the frame with the other free ends having means to receive a draw-string for tightening the free ends of the cords and for binding the cords onto the stack of articles on the base, a second draw-string having sliding connections with intermediate portions of the cords for retaining the stacked articles in place when the first-mentioned draw-string is loosened.

The invention consists in the novel construction, arrangement and combinations of parts hereinafter more particularly described and claimed.

In the drawings:

Figure 1 is a view in elevation of a base or frame of a packing device.

Figure 2 is a view in elevation of one face of

2

the frame shown as having a covering applied thereto.

Figure 3 is a top plan view of the frame shown in Figure 1.

Figure 4 is a top plan view of the covered frame shown in Figure 2.

Figure 5 is a view in elevation of the opposite or other face of the covered frame shown in Figure 2.

10 Figure 6 is a side view in elevation of the covered frame.

Figure 7 is a view in elevation showing a fabric covering for packed articles having a pair of flaps overlapped.

15 Figure 8 is a view in elevation showing the pack in condition for transportation.

Figure 9 is a side view of the completed pack.

Figure 10 is a side view of the pack partially opened.

20 Figure 11 is an enlarged fragmentary side view showing the cords for tying the pack in a compact mass.

Figure 12 is an enlarged view of the frame showing the connections for a shoulder strap, and

25 Figure 13 is a fragmentary view in elevation showing a modified form of connection for the binding cords.

Referring more particularly to the drawings, 15 designates a base which is in the form of a 30 rectangular frame made of wood, a light metal or other suitable materials. The frame includes top and bottom bars 16 and 17, side bars 18 and a cross bar 19 for supporting the upper ends of shoulder straps 20. A plurality of spaced eyes 21 are screwed into the bars forming the frame. When the bars are formed of aluminum, said eyes are secured to the frame in any well-known manner.

A fabric cover has a body portion 25 stretched 35 across one face of the frame as shown in Figure 5 while the free ends 26 are brought in close association (Figure 2) at the other side of the frame. A lace 27 is threaded through eyelets 28 formed in the edges of the ends or flaps 26. The cover is held against slippage on the frame since the lace is passed around the top and bottom bars 16 and 17, the free ends of said lace being secured by a suitable knot 29.

Each shoulder strap 20 has an upper loop 30 received by the cross bar 19 and the straps extend through a reinforced opening 31 in the body 25 of the fabric covering for the frame 15 (Figure 5). The straps are carried downwardly and the free ends 32 thereof are connected to a well-known form of buckle 33 (Fig. 12) which is at-

tached to a loop 34 of a strap 35. Said strap is secured at 36 to a respective side bar 18 of the frame 15 where said strap enters a reinforced opening 37 of the fabric covering for the frame.

It will be noted from Figures 6 and 12 that reinforced openings 40 are formed in those portions 41 of the fabric covering for the frame 15 where the covering passes around the side bars 18 of said frame. The screw eyes 21 extend from said side bars and through the reinforced openings in the fabric.

Cords 45 attached to the eyes 21 are trained outwardly from the covered frame 15 and around a wrapper or cover 46 (Figs. 9 and 10) for the pack 47 which is neatly stored on said covered frame. Each cord has one end connected to an eye 21 by two half hitches 48 (Fig. 11). The free end of said cord is bound at 49 to the main body of the cord by a piece of twine. When plastic cords or ropes are used instead of the fibrous cords 45 the free end may be secured in place by a liquid plastic. The opposite free end of each cord 45 has affixed thereto a ring 50. The method of connection is identical with that shown for the opposite end just described and therefore the same reference numerals are applied to like parts. A second ring 51 is attached to an intermediate portion of each cord 45 by two half-hitches 52 of said cords.

A draw-string 55 in the form of a rope or stout cord has one end 56 attached to the ring 51—a. The other end of said cord is threaded through the rings 51 and connected to the ring 51—a diametrically opposite the point of attachment of the other end 56 of the cord by two half-hitches 57 and a bow knot 58. The rope 55 has a free run through the rings 51 so that it may be drawn taut for retaining the intermediate portion of the pack intact.

A second draw-string 60 has one end 61 attached to the ring 50—a while the other end is threaded through the rings 50 and attached at 62 to the ring 50—a diametrically opposite the end 61. This cord or draw-string is free-running through the rings 50. The attachment 62 is identical with the attachment 57—58 and may be released readily when desired.

The end 56 of the rope 55 and the end 61 of the rope 60 are connected to the respective rings 51—a and 50—a in a manner identical with that shown at 48 and 49 for the substantially radial cords 45. Therefore the reference numerals 48 and 49 will be applied to similar parts of the ends 56 and 61 without further description.

The cords 45 vary in length according to their positions on the frame 15. Diametrically opposite cords (Figure 8) are of equal length and those cords adjacent the corners of the frame are progressively longer than those at the centers of the end bars 16—17 and the side bars 18 so that the rings 50 will fall approximately in the circumference of an ellipse at the top of the pack when the draw-string 60 has been tightened properly.

The cover 46 for the stacked articles 65 (Figure 10) is substantially rectangular and is folded over the articles; the end flaps 66 and 67 providing the final closure. These flaps may be shifted to inoperative positions when desired for the removal of articles from the pack after the draw-string 60 has been loosened.

In Figure 13 a modified form of connection between the cords 45 and the screw eyes 21 is illustrated. In this case, a snap hook 68 is attached directly to the inner end of each cord for removably connecting said ends to the screw eyes.

When the pack is formed the covered frame 15 is placed flat upon a table with the lacing 27 uppermost and the shoulder strap spread outwardly (Figure 2). The cover or wrapper 46 which may be canvas or some form of waterproof material is laid upon the peripheral portions extending beyond the periphery of the frame. The articles to be transported are stacked neatly on the frame and the side sections of the cover 46 are drawn together over the stacked articles. The end flaps 66 and 67 are then positioned as shown in Figure 7.

The free end of the draw-string 60 is pulled up tight while the rings 50 are arranged in uniform positions shown in Figure 8, and are limited to such positions by their varying lengths. The free end of the draw-string 55 is next drawn up tight and secured to the ring 51—a.

If desired, a reinforcing cord 70 may be received by certain of the rings 50 so that it will assume a triangle when drawn up taut at its ends connected to the free end of the draw-string 60. The cord 70 may be a continuation of said draw-string.

When it is desired to obtain one or more articles from the pack, it is only necessary to loosen the draw-string 60 and cord 70 when employed. This leaves the pack in standing condition, shown in Figure 10, so that it will not be necessary to repack the articles. The flaps of the cover 46 are returned to proper positions and the draw-string is tightened over the pack. If necessary, the draw-string 55 is then tightened.

I claim:

1. A harness for a pack comprising a frame forming a base, cords radiating from the periphery of the frame, a ring on the free end of each cord, a second ring connected to an intermediate portion of each cord, a draw-string threaded through each of the first-mentioned rings, said draw-string having a ring on one end thereof for securing of the other end of the draw-string when drawn up tight, a second draw-string threaded through the second-mentioned rings, said draw string having a ring upon one end for securing of the opposite end of the string.

2. A harness for a pack comprising a rectangular frame having screw eyes at spaced intervals along the periphery of the frame, a cord attached at one end to a screw eye, there being a cord for each eye, a ring connected to the other end of each cord, the rings forming a series at one face of the pack, a draw-string received by the rings for drawing the free ends of the cords tight on the pack, a second series of rings arranged around the sides of the pack, each of said rings being attached to an intermediate portion of an adjacent cord, a second draw-string received by the second series of rings for retaining the side walls of the pack in position.

NORMAN D. ASHWOOD.
